United States Patent Office.

FRANCIS K. WAY, OF SPRINGFIELD, OHIO.

Letters Patent No. 73,270, dated January 14, 1868.

IMPROVED MACHINE FOR TWISTING WAX-ENDS.

The Schedule referred to in these Letters Patent and making part of the same.

TO ALL WHOM IT MAY CONCERN:

Be it known that I, FRANCIS K. WAY, of Springfield, in the county of Clark, and State of Ohio, have invented certain new and useful Improvements in Machines for Twisting Waxed Ends, &c.; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to machines for twisting thread for waxed ends, or for similar purposes, and consists of a novel arrangement of mechanism by which the threads may be quickly and conveniently twisted. In the drawings—

Figure 1 is a perspective view,

Figure 2 is an end view, and

Figure 3 is a side or edge view.

In constructing my machine, I make a platform, A, of wood or any other suitable material, and of any size and shape desired. Upon this platform, and near one end, I erect the standard B, having the two legs *a* *b*, as shown in figs. 1 and 2. On or near the upper end of the standard B, I mount the large driving-pulley C, with its bearings on or in the standard. In each of the legs *a* and *b*, I place an arbor, D, with spring-clips *e*, having a sliding clamp, *d*, as shown in figs. 1 and 3. These arbors D have their bearings in the legs *a* and *b*, and project far enough through to have the small pulleys E and F rigidly attached to them. In order that the bearings of the arbors D may also act as supports for them, I have projections *e*, which form parts of the legs *a* *b*, and through which the arbors D pass. Near the opposite ends of the platform A, I place a hook, *f*. The large pulley C, I provide with a handle, *g*, for convenience in turning it. Around the large pulley C and the small pulleys E and F, I place the belt *h*, as shown in all the figures.

In operating my machine, I place the threads *i* over the hook *f*, and their ends in the clips *e*, and fasten by sliding up the clamps *d*; then revolve the large pulley C by means of the handle *g*. When the pulley C revolves, the pulleys E and F are turned rapidly, and with them the arbors D, which twist the threads *i*, so as to fit them for wax-ends or similar purposes.

In this way, by a simple, easy, and cheap arrangement of mechanism, I am able to furnish shoemakers, saddle and harness-makers, and others, with a convenient device for twisting their thread for wax-ends. The same device may be very conveniently used for many other similar purposes, when desired.

Having thus described my invention, what I claim is—

The arbors D, provided with the spring-clips for holding the threads, and pulleys for imparting motion, in combination with the driving-pulley C, all mounted in the frame B, and arranged to operate substantially as and for the purpose herein set forth.

FRANCIS K. WAY.
